(57) **CLAIM**

The ornamental design for a camcorder, as shown and described.

DESCRIPTION

FIG. 1 is a front perspective view of a camcorder showing our new design;

FIG. 2 is a rear perspective view thereof with the monitor panel in an opened position;

FIG. 3 is a front view thereof;

FIG. 4 is a rear view thereof;

FIG. 5 is a top plan view thereof;

FIG. 6 is a bottom view thereof;

FIG. 7 is a right side view thereof; and,

FIG. 8 is a left side view thereof.

Those portions of the drawings shown in broken lines are unclaimed subject matter and form no part of the claimed design or of a specified embodiment thereof.

1 Claim, 8 Drawing Sheets
